CLAIM

We claim the ornamental design for a cryostat, as shown and described.

DESCRIPTION

FIG. 1 is a front, right, and top perspective view of a cryostat with the optional insert and the cover removed to disclose details of the cryostat not otherwise discernible from the drawings;

FIG. 2 is another front, right, and top perspective view thereof at a slightly different angle;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and

FIG. 8 is a bottom plan view thereof.

FIG. 9 is a front, right, and top perspective view of a cryostat showing the optional insert in place and with the cover removed to disclose details of the cryostat not otherwise discernible from the drawings;

FIG. 10 is a front, right, and top perspective view thereof with the optional insert elevated;

FIG. 11 is a front elevational view thereof with the optional insert in place;

FIG. 12 is a rear elevational view thereof;

FIG. 13 is a right side elevational view thereof;

FIG. 14 is a left side elevational view thereof;

FIG. 15 is a top plan view thereof; and

FIG. 16 is a bottom plan view thereof.

FIG. 17 is a front, right, and top perspective view of a cryostat showing the cover in closed configuration and with the optional insert removed to disclose details of the cryostat not otherwise discernible from the drawings;

FIG. 18 is a front, right, and top perspective view thereof showing the cover in open configuration;

FIG. 19 is a front elevational view thereof showing the cover in closed configuration;

(Continued)

FIG. 20 is a rear elevational view thereof;
FIG. 21 is a right side elevational view thereof;
FIG. 22 is a left side elevational view thereof;
FIG. 23 is a top plan view thereof; and,
FIG. 24 is a bottom plan view thereof.
The broken lines depict portions of the cryostat that form no part of the claimed design.
